UNITED STATES PATENT OFFICE

2,377,497

AIR CONTROLLED FUEL BURNER

Robert C. Hopkins, Alliance, Ohio

Application January 7, 1943, Serial No. 471,589

7 Claims. (Cl. 158—99)

The invention relates to fuel burners and more particularly to a gas burner having air operated means controlled by the furnace temperature for regulating the gas supply to the burner.

Burner controls such as are now in general use are ordinarily operated by expensive apparatus which includes motors specially built and adjusted so as to produce a reciprocating motion whereby the control parts are moved forward and back from open to closed position by mechanical means between the motor and burner. In large furnaces such apparatus runs into considerable expense and is also quite liable to breakage, wear and failure of adjustment, causing additional expense as well as delay in production.

The present invention therefore contemplates the provision of a simple, inexpensive and efficient means for controlling a burner, which overcomes the above objections to the present form of control means.

An object of the invention is to provide a burner having a gas tube and a mixing chamber telescopically connected together with means for producing relative sliding movement between the gas tube and mixing chamber to simultaneously control the gas flow and air combustion at the burner nozzle.

Another object is to provide air operated means controlled by the furnace temperature for producing relative movement between the gas tube and the mixing chamber.

A further object is to provide a metal bellows, or the like, operating with the air pressure required for combustion to regulate the flow of gas and air of combustion.

A still further object is the provision of a burner of the character referred to having a gas tube closed at the end toward the burner nozzle and provided with a series of slots adjacent said end to permit the flow of gas, and a mixing chamber slidably mounted upon said gas tube and movable over said slots to regulate the gas flow therefrom.

Another object of the invention is to provide a burner of the character just described in which air under pressure is admitted tangentially to the mixing chamber thus setting up a spinning motion inside the mixing chamber, the gas being introduced at the center of the mixing chamber and therefore in the center of the spinning air.

Still another object is to provide a burner of this character in which a ring is carried by the mixing chamber and arranged to be adjusted relative to the nozzle plate to regulate the air for combustion.

5 A further object is to provide a burner of this character in which the ring is spaced from the tip of the mixing chamber so that the premixture of air and gas within the mixing chamber itself is completed with second and third stage air flow through the orifice between the ring and the mixing chamber and also between the outside of the ring and the nozzle plate of the burner.

10 A still further object of the invention is to provide a burner of this character in which means is provided for adjusting the position of the gas tube relative to the nozzle of the burner.

15 Another object is to provide such a burner in which the gas flow and air for combustion at the burner nozzle are automatically regulated and the desired proportion can be established and maintained between the gas and air, and at the same time a manually operated blast gate controls the admission of air to the burner casing.

20 Still another object is the provision of a burner of the type referred to in which the metal bellows has a sufficient amount of spring quality to operate the mixing chamber relative to the gas tube in one direction which the compressed air operates the mixing chamber in the opposite direction against the spring action.

25 A still further object of the invention is the provision of an elongated burner casing having a gas tube extending longitudinally therethrough, closed at the end toward the burner nozzle and provided with a series of slots adjacent this end, a mixing chamber being slidably mounted upon the gas tube and having tangential openings therein, means for admitting an air blast to the

30 interior of the casing, a ring carried by the mixing chamber and spaced therefrom, a metal bellows, or cylinder and piston, located adjacent to the burner casing, a low pressure compressed air line leading thereto, a solenoid or motor valve in said air line, a pyrometer and thermocouple controlling said valve, and linkage connecting the metal bellows or piston with the slidable mixing chamber for automatically adjusting the same to control the gas flow and air for combustion.

35 40 45 The above objects together with others which will be apparent from the drawings and following description, or which may be later referred to, may be attained by constructing the improved burner in the manner illustrated in the accompanying drawing, in which—

40 45 50 Figure 1 is a diagrammatic view showing the improved burner operatively connected to a furnace;

55 Fig. 2, an enlarged top plan view of the burner;

Fig. 3, a vertical longitudinal sectional view through the burner partly in elevation;

Fig. 4, a transverse section through the burner, at the mixing chamber, taken as on the line 4—4, Fig. 3;

Fig. 5, a transverse sectional view through the burner, at the nozzle plate, taken as on the line 5—5, Fig. 3; and

Fig. 6, an end elevation of the rear or outer end of the burner.

Similar numerals refer to similar parts throughout the drawings.

The burner casing, indicated generally at 10, may be substantially cylindrical and closed at its rear end by the end plate 11 connected thereto as 15 by the screws 12.

The upper side of the casing 10 is provided, near the rear end thereof, with the air inlet opening 13 for receiving an air blast from the air line 14.

If desired a blast gate may be provided to control and regulate the air blast entering the casing at this point. This blast gate may be in the form of a slidable plate 15 mounted in a housing 16 attached to the upper side of the casing as by screws 17.

For the purpose of operating the blast gate a rod 18 may be fixed thereto, as by the bracket 19 and screws 20, and slidably located through a bore 21 in the boss 22 formed upon the housing 16, the outer end of the rod having a handle 23 connected thereto. A set screw 24 may be threaded through the boss 22 for frictional engagement with the rod 18 to hold the blast gate in adjusted position.

A gas tube 25 extends longitudinally through the central portion of the casing 10 being adjustably mounted through the end blast 11 as by the screw threads 26. The outer end of the gas tube is attached to a coupling 27 to which may be connected one or more gas pipes 28 leading from a suitable source of supply.

The forward end of the gas tube 25 terminates at a point spaced from the nozzle plate 29 which may be attached to the forward end of the casing 10 as by screws 30.

This end of the gas tube is closed as by an end plate or plug 31 and a series of longitudinal slots 32 is milled or otherwise formed in this end portion of the gas tube to permit gas flow therethrough.

The mixing chamber, indicated generally at 33, is provided with a plurality of tangential openings 34 so that the air blast from the interior of the casing may enter the mixing chamber tangentially setting up a spinning motion within the mixing chamber. The gas is introduced from the slots 32 in the gas tube into the central portion of the mixing chamber and thus within the center of the spinning air.

The forward end of the mixing chamber is preferably in the form of a hollow truncated cone as indicated at 35. A ring 36, having the conical forward portion 37, is concentrically spaced around the conical end 35 of the mixing chamber, being preferably connected thereto as by the radial webs 38.

The mixing chamber is provided with a sleeve 39, slidably mounted upon the gas tube 25 and so positioned relative to the inner end of the gas tube that it may cut off any part or all of the slots 32 so as to regulate the gas flow therethrough.

For the purpose of slidably moving the mixing chamber upon the gas tube a metal bellows, or cylinder and piston, is provided.

In the drawings a metal bellows is shown indicated generally at 40 and provided with the rod 41 connected to the lower end of a lever 42, fulcrumed at 43 upon a bracket 44 connected to, or formed upon, the end plate 11. The cylinder or bellows 40 is also suspended from the burner casing as by a bracket 45 which may be attached to the casing as by screws 46.

The upper end of the lever 42 is pivotally connected as at 47 to the outer end of a rod 48, slidably located through an opening 49 in the end plate 11, and having its other end connected to the depending lug 50 upon the sleeve 39.

For the purpose of operating the bellows, or cylinder and piston, a low pressure, compressed air line 51 is connected thereto and provided with a solenoid or motor operated valve 52, as shown in Figure 1.

In this figure a burner is shown connected to a furnace, a portion of which is indicated at 53. A thermocouple 54 is located in the furnace and connected by wires 55 to a pyrometer 56 which may be of either the plain or recording type.

The wires 57 and 58 lead from a suitable source of electric energy, the wire 57 leading to the solenoid or motor valve 52 and the wire 58 leading to the pyrometer 56, a wire 59 connecting the pyrometer and valve.

In assembling the burner the gas tube 25 is adjusted, by means of the screw threads 26 to the desired position within the burner, placing the slots 32 therein at the required distance from the nozzle plate 29.

The mixing chamber 33 is slidably mounted upon the forward end portion of the gas tube in such position that in the full operation thereof upon the gas tube the mixing chamber will move from one end of the slots 32 to the other so that it may assume any position from fully opened to fully closed slots.

As the mixing chamber is moved forward it entirely closes the slots 32 and the conical portion 37 of the ring 36 contacts the conical opening 60 in the nozzle plate 29 cutting off air of combustion between the ring and nozzle plate but still permitting a flow of air between the conical portion 35 of the mixing chamber and the ring.

As the mixing chamber is moved backward it entirely uncovers all of the slots 32, giving the maximum gas flow and moves the ring 37 a corresponding distance away from the nozzle plate thus permitting the maximum air flow.

At any intermediate point the established ratio of gas and air is thus maintained.

In the position shown in Figure 3 of the drawings the gas slots 32 are slightly more than half closed and the space between the conical portion 37 of the ring and the opening 60 of the burner plate is correspondingly reduced.

In actual use the air pressure may be anywhere from four ounces up to sixteen ounces, or even greater if desired, and the gas pressure ranges from four ounces up to the maximum air pressure.

Although a cylinder and piston may be provided for operating the sliding mixing chamber a metal bellows, such as shown at 40 in the drawings, is preferred because the bellows has sufficient spring quality to cause it to assume a closed position under normal air pressure thus moving the mixing chamber to a position to fully uncover the slots 32, while when the valve 52 is opened air pressure admitted to the bellows through the pipe 51 moves the mixing chamber in the opposite direction, against the spring action of the bellows.

This construction obviates the necessity of an additional spring means which is required where a cylinder and piston are used in place of the bellows.

The pipe 51 is connected to a suitable source of low pressure, compressed air, the pressure being of any intensity from four ounces up to the maximum available for operating the burner.

The blast gate 15 may be manually adjusted, by means of the handle 23 and held in adjusted position by the set screw 24, to regulate the air blast admitted to the interior of the burner casing, as may be desired, and with any established setting of the blast gate the control of the burner by the mechanism above described is automatic, the flow of air and gas to the burner nozzle being proportionately increased or decreased to meet the demands of the furnace.

Through the thermocouple 54 and pyrometer 56 the valve 52 is operated to increase or decrease the air pressure to the bellows operating the slideable mixing chamber to regulate the air and gas flow as required by the furnace. If desired the valve 52 and its solenoid may be of a type capable of gradual opening and closing although this is not entirely essential since the spring quality of the metal bellows 40 will cause the opening and closing movement thereof to be gradual so as to provide for continuous regulation of the quantities of air and gas admitted to the burner.

Although the invention is above described as a gas burner and is especially adapted for burning natural or producer gas it should be understood that without any change in the construction of the burner fuel oils may be atomized and very efficiently burned therein.

I claim:

1. A burner including a casing having a nozzle at one end, means for admitting air under pressure to the casing, a gas tube located in the casing and terminating in a closed end spaced from the nozzle, there being openings in the gas tube adjacent to said closed end, means for admitting gas to the gas tube, a mixing chamber slidably mounted upon the gas tube and positioned to slide over said openings, means for admitting air tangentially into the mixing chamber from the casing to produce a spinning motion of the air in the mixing chamber around the gas introduced at the center of the mixing chamber through said openings and means for producing relative sliding movement between the mixing chamber and gas tube for regulating the gas flow from the gas tube to the mixing chamber.

2. A burner including a casing having a nozzle at one end, means for admitting air under pressure to the casing, a gas tube located in the casing and terminating in a closed end spaced from the nozzle, there being openings in the gas tube adjacent to said closed end, means for admitting gas to the gas tube, a mixing chamber slidably mounted upon the gas tube and positioned to slide over said openings, means upon the exterior of the mixing chamber cooperating with the nozzle for regulating the air of combustion at the nozzle of the burner and means for producing relative sliding movement between the mixing chamber and gas tube for regulating the gas flow from the gas tube to the mixing chamber and for regulating the air of combustion at the nozzle.

3. A burner including a casing having a nozzle at one end, means for admitting air under pressure to the casing, a gas tube located in the casing

and terminating in a closed end spaced from the nozzle, there being openings in the gas tube adjacent to said closed end, means for admitting gas to the gas tube, a mixing chamber slidably mounted upon the gas tube and positioned to slide over said openings and a compressed air operated device for producing relative sliding movement between the mixing chamber and gas tube for regulating the gas flow from the gas tube to the mixing chamber.

4. A burner including a casing having a nozzle at one end, means for admitting air under pressure to the casing, a manually operated blast gate for controlling the admission of air to the casing, a gas tube located in the casing and terminating in a closed end spaced from the nozzle, there being openings in the gas tube adjacent to said closed end, means for admitting gas to the gas tube, a mixing chamber slidably mounted upon the gas tube and positioned to slide over said openings for regulating the gas flow from the gas tube to the mixing chamber.

5. A burner including a casing having a nozzle at one end, means for admitting air under pressure to the casing, a gas tube located in the casing and terminating in a closed end spaced from the nozzle, there being openings in the gas tube adjacent to said closed end, means for adjusting the gas tube relative to the nozzle, means for admitting gas to the gas tube, a mixing chamber slidably mounted upon the gas tube and positioned to slide over said openings for regulating the gas flow from the gas tube to the mixing chamber.

6. A burner including a casing having a nozzle at one end, means for admitting air under pressure to the casing, a gas tube located in the casing and terminating in a closed end spaced from the nozzle, there being openings in the gas tube adjacent to said closed end, means for admitting gas to the gas tube, a mixing chamber slidably mounted upon the gas tube and positioned to slide over said openings, means for admitting air from the casing to the mixing chamber, a ring carried by the mixing chamber and spaced from the exterior thereof so that air of combustion may pass from the casing between the mixing chamber and ring and between the ring and nozzle, the mixing chamber being slidable upon the gas tube for regulating the gas flow from the gas tube to the mixing chamber and for regulating the air of combustion at the nozzle.

7. A burner including a casing having a nozzle at one end, means for admitting air under pressure to the casing, a gas tube located in the casing and terminating in a closed end spaced from the nozzle, there being openings in the gas tube adjacent to said closed end, means for admitting gas to the gas tube, a mixing chamber slidably mounted upon the gas tube and positioned to slide over said openings, means for admitting air tangentially into the mixing chamber from the casing to produce a spinning motion of the air in the mixing chamber around the gas introduced at the center of the mixing chamber through said openings, means upon the exterior of the mixing chamber cooperating with the nozzle for regulating the air of combustion at the nozzle of the burner and means for producing relative sliding movement between the mixing chamber and gas tube for regulating the gas flow from the gas tube to the mixing chamber.

ROBERT C. HOPKINS.
